Primary Examiner — Dana L Meyrow*(74) Attorney, Agent, or Firm* — Quarles & Brady LLP(57) **CLAIM**

The ornamental design for a container with cap and base, as shown and described.

DESCRIPTION

FIG. 1 is an isometric view of a top, front, and left side of an ornamental design for a container with cap and base; FIG. 2 is a front elevational view of the container with cap and base of FIG. 1; FIG. 3 is a rear elevational view of the container with cap and base of FIG. 1; FIG. 4 is a left side elevational view of the container with cap and base of FIG. 1; FIG. 5 is a right side elevational view of the container with cap and base of FIG. 1; and, FIG. 6 is a top plan view of the container with cap and base of FIG. 1.

The dash-dash-dash lines are included for the purpose of illustrating portions of the container with cap and base that form no part of the claimed design.
